UNITED STATES PATENT OFFICE

2,210,943

SEWING MACHINE NEEDLE THREADER

John C. Lounsbury, Washington, D. C.

Application July 17, 1939, Serial No. 284,988

5 Claims. (Cl. 112—225)

This invention relates to sewing machine needle threaders, and has for an object to provide an attachment which may be used when the needle is to be threaded and which will accurately thread the needle in a fraction of the time it would take to thread the needle by hand.

A further object is to provide a device of this character which will not lock until the needle is inserted, and which in the event of trouble caused by kinking of the thread or any other reason, can be easily unlocked manually to free the needle without breakage.

A further object is to provide a device of this character in which a single spring is employed to force the threading pin through the eye of the needle and return the pin to neutral position.

A further object is to provide a device of this character in which the trigger and the L bar both move in the same direction, at the same time, so that there is very little compression on the spring, thus promoting the long life of the spring.

A further object is to provide a device of this character in which a single spring operates all the moving parts.

A further object is to provide a device of this character in which the trigger automatically lifts itself into position and locks if the needle is in proper position to be threaded and if the needle is not in proper place the L bar will instantly drop and automatically release the trigger.

A further object is to provide a device of this character in which the mechanical construction is such that the most pressure is exerted on the threading pin when the pin is forcing the thread through the eye of the needle, with very little resistance on the return stroke of the pin.

A further object is to provide a device of this character which receives different sizes of needles, which will center the needle accurately regardless of size, and which may be easily applied to the sewing machine and will employ an adjustable cam to bear against the long leg of the presser foot and dispose the device in proper position with relation to the path of the needle to properly thread the needle.

With the above and other objects in view the invention consists of certain novel details of construction and combination of parts hereinafter fully described and claimed, it being understood that various modifications may be resorted to within the scope of the appended claims without

departure from the spirit or sacrificing any of the advantages of the invention.

In the accompanying drawing forming part of this specification:

Figure 1 is a rear elevation of a sewing machine needle threader constructed in accordance with the invention.

Figure 2 is a side elevation of the needle threader in applied position.

Figure 3 is a top plan view of the needle threader with a portion broken away to show the presser foot.

Figure 4 is a longitudinal sectional view taken on the line 4—4 of Figure 2 showing the threading pin in neutral position.

Figure 5 is a view similar to Figure 4 but showing the trigger in locked position and the threading pin in position to thread the needle.

Figure 6 is a view similar to Figure 5 but showing the trigger at the moment of release when the threading pin has pushed a loop of the thread through the eye of the needle to be clamped stationary while the needle makes its up stroke.

Figure 7 is a detail sectional view showing the threading pin pushing a loop of the thread against the bottom of the longitudinal groove of the needle.

Figure 8 is a detail sectional view showing the threading pin as having pushed a loop of the thread through the eye of the needle.

Figure 9 is a detail sectional view showing the loop of the thread clamped stationary while the needle makes its up stroke after being threaded.

Figure 10 is a detail side elevation of the threading pin showing the concave tip to receive the thread.

Figure 11 is a detail plan view showing the shape of the needle receiving opening of the device to properly receive the needle and thread.

Referring now to the drawing in which like characters of reference designate similar parts in the various views, 10 designates the needle, 11 the presser foot stem, 12 the long leg of the presser foot, and 13 the short leg of the presser foot, these being conventional sewing machine parts.

In carrying out the invention a substantially rectangular casing 14 is provided, open at the bottom and closed at the top by integral top wall 15. A bottom plate 16 closes the bottom of the casing and is provided at the front end with forwardly and downwardly extending feet 17, and at the rear end with a rearwardly and downwardly extending foot 18 to support the device on the

sewing machine 19 above the conventional toothed feed 20 of the sewing machine, as best shown in Figure 2.

A gauge plate 21 is disposed on the bottom of the bottom plate 16 and is provided at the front end with depending lugs 22 which engage the sewing machine on opposite sides of the feed 20 and space the device thereabove. The gauge plate is provided with an integral upstanding guide pin 23, best shown in Figures 1 and 2, adapted to enter between the presser feet 12 and 13, as best shown in Figure 3. The gauge plate is provided centrally with a vertical wall portion 24 having an opening 25 therein to permit the long leg 12 of the presser foot to pass therethrough for engagement with a cam 26, best shown in Figure 2.

The cam 26 is provided with an eccentric cam surface 27, and is mounted on a cylindrical pin 28 which rises from the bottom plate 16. A screw 29 is passed through the pin 28, upper horizontal portion 30 of the gauge plate, and bottom plate 16 of the casing, and is threaded into the top wall 15 of the casing. Dowel pins 9 on the bottom plate are engaged in the casing wall to 25 coat with the screw in assembling the parts.

Formed integral with the casing is a partition wall 31 having an opening 32 formed vertically therein and opening through the top wall and bottom plate to receive the needle 10. A V shaped opening is formed in the front wall of the casing to provide converging guide surfaces 33 adapted to direct a loop of the thread 34 into the needle receiving opening 32, as best shown in Figures 3 and 11. The needle receiving opening 32 is provided with a V shape extension 35 to receive the needle. Opposite the extension the opening 32 is provided with a slot 36. The loop of the thread lodges in this slot and is thus properly positioned with respect to the eye of the needle to be pushed 40 through the eye by the threading pin.

The threading pin 37, as shown in detail in Figure 10, is provided with a concave surface 38 at its tip to receive the thread. The threading pin is slidably received in an opening 39 formed 45 through the division wall 31.

An L shaped lever 40 is pivoted at its elbow, as shown at 41, near one rear corner of the casing. The long leg of the L shaped lever is engaged through an opening 42 in the threading pin, the 50 walls of the opening being reversely curved, as shown in Figure 10, to permit the threading pin rocking relatively to the needle during its rectilinear movement through the opening 39.

A trigger 43 is pivotally mounted on a pivot pin 55 44 which rises from the bottom plate 16 of the casing between the threading pin and the pivot pin 41 of the L shaped lever, and latterly of the L shaped lever. A slot 45 is formed in the trigger to receive this pivot pin so that the trigger may 60 have rectilinear as well as pivotal movement. The trigger is provided with a right angularly disposed extension 46 which projects from the inner end of the trigger and in one position of the trigger engages the division wall 31 for a 65 purpose which will be presently explained. The trigger is provided in its rear longitudinal edge with a bayonet slot 47 which receives a hook 48 which projects from the edge of an opening 49 in the rear wall of the casing. Through this latter opening the trigger projects exteriorly of 70 the casing.

A U shaped spring 50 is engaged around and spaced from the assembly screw 29. One leg of the spring is secured to the trigger near the slot 75 47 and the other leg of the spring is secured to

the short free leg of the L shaped lever. This spring transmits movement of the trigger to the L shaped lever and threading pin as will be presently described.

A substantially arcuate catch 51 is pivotally mounted on a pivot pin 52 which rises from the bottom plate of the device on the opposite side of the partition wall 31 from the L shaped lever. One end of the catch bears against the trigger 43 adjacent the extension 46. The opposite end 10 of the catch forms a jaw 53 which coacts with a fixed jaw 54 on the inner face of the front wall of the casing to clamp the loop of the thread stationary after the needle has been threaded by the threading pin.

In operation the device is placed with the legs 17 and 18 on the sewing machine and slid forwardly on the feed 20 with the guide pin 23 engaged between the presser feet 12 and 13 until the presser foot 12 engages the cam 26. The eccentric surface 27 of the cam automatically disposes the device with its longitudinal median line disposed obliquely to the central median line of the feed 20 in which position the threading pin is properly located to pass accurately through 25 the eye of the needle.

The fly wheel of the sewing machine is then turned to lower the needle 10 through the opening 32, as shown in Figure 7. The operator then pulls the trigger from the position shown in Figure 4 to the position shown in Figure 5 which is the locked or cocked position ready to operate. During this movement of the trigger the spring 50 has been placed under compression to exert pressure upon the short leg of the L shaped lever 30 and cause the long leg of the lever to press the loop of the thread against the bottom of the longitudinal slot in the needle. Also at the same time the extension 46 has rocked the arcuate catch 51 on its pivot to open the jaw 53 from the 40 stationary jaw 54.

The fly wheel is then turned back to raise the needle 10 through the opening 32. At the moment the eye 55 of the needle enters the opening 32 the tensioned spring 50 urges the threading 45 pin through the eye of the needle and the loop of the thread is carried between the open jaws 53 and 54 as shown in Figure 8. Simultaneously the long leg of the L shaped lever strikes against extension 46 and pushes the trigger forwardly to 50 unlock the hook 48 from the trigger as shown in Figure 6 and permit the spring 50 to expand and rock the trigger to the neutral position shown in Figure 4. During such movement the trigger pushes against the curved end of the catch 51 55 and rocks the catch on the pivot 52 to close the jaw 53 and bind the loop of the thread stationary against the jaw 54 as shown in Figure 9. Meanwhile at the moment the trigger clears the hook 48 the spring 50 pushes against the trigger and 60 swings the trigger extension 46 against the long leg of the L shaped bar to instantly withdraw the threading pin 37 to its neutral position so that the threaded needle 10 may continue its upward stroke clear of the threading device, as shown in 65 Figure 9.

It will be noted that upon release of the trigger by the operation of the threading pin passing through the eye of the needle, the trigger and the L lever both move in the same direction at 70 the same time during withdrawal stroke of the pin so that there is very little compression on the spring thus promoting the long life of the spring.

It will be further seen that the operation of 75

the trigger is automatic when the needle is in proper position but if the needle is not in place the L lever can move sufficiently to automatically release the trigger.

5 It will also be noted that the greatest spring pressure is exerted on the threading pin when the pin is forcing the thread through the eye of the needle and that very little expansion of the 10 spring takes place during the return stroke of the pin.

Also the trigger is in position to be easily reached for unlocking of the device manually if the thread is kinked or otherwise distorted with a tendency to jam in the threading device.

15 From the above it is thought that the construction and operation of the invention will be fully understood without further explanation.

What is claimed is:

20 1. A sewing machine needle threader comprising a casing, means for spacing the casing above a sewing machine feed, a threading pin mounted to slide transversely in the casing, a guide means in the casing in the path of the pin and of the sewing machine needle for receiving a loop of 25 thread, a lever connected to the pin for moving the pin to carry the loop through the eye of the needle, means for clamping the loop of thread stationary while the pin is being withdrawn after the needle is threaded, a trigger adapted to engage the lever and the loop clamping means mounted in the casing for pivotal and rectilinear movement and adapted to be manually cocked, means carried by the casing for releasably holding the trigger in cocked position, and a single 30 spring connected to the lever and to the trigger adapted to be tensioned when the trigger is cocked and adapted to expand and release the trigger as soon as the threading pin passes through the eye of the needle and adapted to simultaneously move the lever to withdraw the pin from the needle and to actuate the loop clamping means.

40 2. A sewing machine needle threader comprising a casing, means for spacing the casing above a sewing machine feed, means connected to the casing adapted to coat with the long and the short leg of the presser foot of a sewing machine for disposing the longitudinal median line of the casing oblique to the longitudinal median line of the feed, a threading pin mounted to slide transversely in the casing, a guide means in the casing in the path of the pin and of the sewing machine needle for receiving a loop of thread, a lever connected to the pin for moving the pin to carry the loop through the eye of the needle, means for clamping the loop of thread stationary while the pin is being withdrawn after the needle is threaded, a trigger adapted to engage the lever and the loop clamping means mounted in the 45 casing for pivotal and rectilinear movement and adapted to be manually cocked, means carried by the casing for releasably holding the trigger in cocked position, and a single spring connected to the lever and to the trigger adapted to be tensioned when the trigger is cocked and adapted to expand and release the trigger as soon as the threading pin passes through the eye of the needle and adapted to simultaneously move the lever to withdraw the pin from the needle and to actuate the loop clamping means.

50 3. A sewing machine needle threader comprising a casing, means for spacing the casing above a sewing machine feed, a threading pin mounted to slide transversely in the casing, a guide means in the casing in the path of the pin and of the sewing machine needle for receiving a loop of thread, a lever connected to the pin for moving the pin to carry the loop through the eye of the needle, means for clamping the loop of thread stationary while the pin is being withdrawn after the needle is threaded, a trigger adapted to engage the lever and the loop clamping means mounted in the casing for pivotal and rectilinear movement and adapted to be manually cocked, means carried by the casing for releasably holding the trigger in cocked position, and a single spring connected to the lever and to the trigger adapted to be tensioned when the trigger is cocked and adapted to expand and release the trigger as soon as the threading pin passes through the eye of the needle and adapted to simultaneously move the lever to withdraw the pin from the needle and to actuate the loop clamping means.

55 and of the sewing machine needle for receiving a loop of thread, an L-shaped lever pivoted at its elbow in the casing and having one leg connected to the threading pin for moving the pin to carry the loop of thread through the eye of the needle, a trigger pivotally and slidably mounted in the casing and having a lateral extension at the pivot adapted to move the lever in a direction to withdraw the pin from the needle after the threading operation, an arcuate catch pivotally mounted in the casing having a jaw at one end and adapted to clamp the loop of thread stationary against the casing and adapted at the other end to engage the trigger and the extension thereof for opening and closing the jaw, means carried by the casing for releasably holding the trigger in cocked position, and a single U-shaped spring connected to the other leg of the lever and connected to the trigger adapted to be tensioned when the trigger is cocked and adapted to expand and release the trigger as soon as the threading pin passes through the eye of the needle and adapted to simultaneously move the lever and the catch to withdraw the pin from the needle and to clamp the loop of thread.

60 4. A sewing machine needle threader comprising a casing, means for spacing the casing above a sewing machine feed, there being a guide opening in the casing adapted to receive the sewing machine needle, said opening having a V-shaped extension on one side to center the needle and having a slot diametrically opposite the V-shaped extension to receive a loop of thread vertically, a threading pin mounted in the casing to slide transversely through said opening and having a concave tip to receive the loop of thread and carry it through the eye of the needle, a lever connected to the pin for moving the pin to carry the loop through the eye of the needle, means for clamping the loop of thread stationary while the pin is being withdrawn after the needle is threaded, a trigger adapted to engage the lever and the loop clamping means mounted in the casing for pivotal and rectilinear movement and adapted to be manually cocked, means carried by the casing for releasably holding the trigger in cocked position, and a single spring connected to the lever and to the trigger adapted to be tensioned when the trigger is cocked and adapted to expand and release the trigger as soon as the threading pin passes through the eye of the needle and adapted to simultaneously move the lever to withdraw the pin from the needle and to actuate the loop clamping means.

65 5. A needle threading device for sewing machines having a presser foot provided with a short leg and a long leg, a feed below the presser foot, and a needle, comprising a casing, legs on the casing for spacing the casing above the feed, a gauge plate connected to the casing adapted to be spaced above the feed, a pin rising from the gauge plate adapted to enter between the legs of the presser foot, a cam adjustably mounted on the gauge plate having an eccentric edge adapted to engage the end of the long leg of the presser foot and dispose the longitudinal median line of the casing oblique to the longitudinal line of the feed, a threading pin mounted to slide transversely in the casing, a guide means in the casing in the path of the pin and of the sewing machine needle for receiving a loop of thread, a lever connected to the pin for moving the pin to carry the loop through the eye of the needle, means for clamping the loop of thread stationary while the pin is being withdrawn after the needle is threaded, a trigger pivotally and slidably mounted in the casing and having a lateral extension at the pivot adapted to move the lever in a direction to withdraw the pin from the needle after the threading operation, an arcuate catch pivotally mounted in the casing having a jaw at one end and adapted to clamp the loop of thread stationary against the casing and adapted at the other end to engage the trigger and the extension thereof for opening and closing the jaw, means carried by the casing for releasably holding the trigger in cocked position, and a single U-shaped spring connected to the other leg of the lever and connected to the trigger adapted to be tensioned when the trigger is cocked and adapted to expand and release the trigger as soon as the threading pin passes through the eye of the needle and adapted to simultaneously move the lever and the catch to withdraw the pin from the needle and to clamp the loop of thread.

is threaded, a trigger adapted to engage the lever and the loop clamping means mounted in the casing for pivotal and rectilinear movement and adapted to be manually cocked, means carried by the casing for releasably holding the trigger in cocked position, and a single spring connected to the lever and to the trigger adapted to be ten-

sioned when the trigger is cocked and adapted to expand and release the trigger as soon as the threading pin passes through the eye of the needle and adapted to simultaneously move the lever to withdraw the pin from the needle and 5 actuate the loop clamping means.

JOHN C. LOUNSBURY.
